(57) **CLAIM**

The ornamental design for a facial cleaning brush, as shown and described.

DESCRIPTION

FIG. 1 is a perspective view of a facial cleaning brush showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1.

The evenly-incremented broken lines in the drawings depict portions of the facial cleaning brush that form no part of the claimed design. The short-dash-long-dash broken lines shown in FIGS. 1 and 9 depict the bounds of the view taken from FIG. 1 and then enlarged in FIG. 9. The boundaries form no part of the claimed design.
